Term of patent 14 years

(Cl. D80—11)

FIG. 1

FIG. 2

FIG. 3

FIG. 4

FIG. 1 is a front perspective view of a map display cabinet, embodying my new design;

FIG. 2 is a cross-sectional view taken on line 2—2 of FIG. 1;

FIG. 3 is a rear perspective thereof on a reduced scale;

FIG. 4 is a front perspective view of a modified form of the map display cabinet illustrated in FIGS. 1 through 3;

FIG. 5 is a cross-sectional view taken on line 5—5 of FIG. 4; and

FIG. 6 is a rear perspective view of FIG. 4 on a reduced scale.

This application is a continuation of my earlier filed copending applications, Serial Numbers D. 77,328, filed November 7, 1963, and D. 77,695, filed December 6, 1963, now abandoned.

The broken line representation of maps in FIGS. 1, 2, 4 and 5 is for illustrative purposes only.

FIG. 5

FIG. 6

I claim:

The ornamental design for a map display cabinet, as shown and described.
